(57) **CLAIM**

The ornamental design for an automobile, toy replica and/or other replicas as shown and described.

DESCRIPTION

FIG. 1 is a front and right perspective view of an automobile, toy replica and/or other replicas, showing our new design; FIG. 2 is a rear and right perspective view thereof; FIG. 3 is a right side elevation view thereof; FIG. 4 is a left side elevation view thereof; FIG. 5 is a front elevation view thereof; FIG. 6 is a rear elevation view thereof; and, FIG. 7 is a top plan view thereof.

The bottom view is omitted because the article is a heavy object.

The broken line showing is included for the purpose of illustrating portions of the automobile, toy replica and/or other replicas and form no part of the claimed design.
